UNITED STATES PATENT OFFICE.

ADAM ANDRECK AND FRANK RUBCZYNSKI, OF TORONTO, ONTARIO, CANADA.

CUE HOLDER.

Application filed January 10, 1922. Serial No. 528,340.

To all whom it may concern:

Be it known that we, ADAM ANDRECK and FRANK RUBCZYNSKI, both citizens of the Republic of Poland, and both residents 5 of the city of Toronto, in the Province of Ontario and Dominion of Canada, have invented certain new and useful Improvements in Cue Holders, of which the following is a specification.

This invention relates to improvements in cue holders, and more particularly to suspension holders for billiard cues and the like, in which the weight of the cue operates the holder to retain the cue therein, and the 15 objects of the invention are to provide simple, inexpensive and practical means of this kind that will retain the cues neatly in a hanging position and prevent them warping by reason of the above-mentioned fact that they are practically sustained in the cue 20 holder by their own weight.

A further object, therefore, is to provide a cue holder that will obviate the necessity for using metal cases or the like to put away 25 cues in and keep them straight.

A still further object is to provide a cue holder of this character that can be locked when the cue is in position.

It is a well known fact that, in the ordinary clip racks now, more or less, in general use, the cues in a short time become bent or warped due to the natural shrinking of the wood, making it impossible to play accurately with them. Our invention, on the 30 other hand, while embodying the simplicity of the ordinary rack, at the same time combines with it the advantages of the metal case in preventing warping at practically no additional cost.

With the foregoing and other objects in view, the invention consists essentially of a slotted plate or strip of metal formed with an intermediate ledge and having a pair of operatively mounted gripping members provided with hinged arms designed to be held in interlocked position by a pin or spindle therethrough extending through the slot in the plate, whereby the holder is slidably mounted to operate the gripping members 45 to open or close on the holder being moved, respectively, upwardly and downwardly, pivoted cam means on the slotted plate whereby the upward and downward movement of the holder is controlled and whereby the holder may be locked in closed position.

In the drawings, like characters of reference indicate corresponding parts in each figure, and in which:

Figure 1 is a front elevation of the holder 60 in closed position with cue therein.

Figure 2 is a vertical section.

Figure 3 is a front elevation of the holder in open position.

Figure 4 is a sectional detail of one of 65 the gripping members.

Referring to the drawings:

A is the cue holder of any suitable material and is here shown as comprising a metal strip or plate 10 narrowed from, approximately, the centre upwards at 11 to form a slideway provided with a vertically extending recess or slot 12 therein. Adjacent to the bottom of the slot 12 is the ledge or rest 13 formed integral with the plate 70 member 10 by folding over the lower end thereof on itself and bending the extremity outwardly. This form of construction is the one illustrated but we do not confine ourselves to it, and the ledge 13 may be formed 75 in any other suitable or convenient manner.

In the folded lower end of the member 10, as here shown, is mounted a bar or pin 14 outwardly bent at right angles at 15 and having enlarged ends 16. 17 are gripping 80 members partly S-shaped loosely mounted on the bent ends 15 and hingedly connected at their opposite ends to the operating arms 18 which, in turn, are adapted to overlap each other at 19 and to receive therethrough 85 in this position a securing spindle or pin 20 designed to extend into a wall or other support through the slot 12 whereby the cue 90 holder is suspended.

21 is a pivotally mounted cam member 95 adjacent to the slot 12 and formed with a ledge or shoulder 22 adapted to engage with the spindle 20, as hereinafter more fully described, to lock a cue in the holder and to retain the gripping members in open position 100 to receive the cue. 23 is an ordinary billiard cue and 24 is a lining of leather or other suitable material for the gripping members 17 to prevent said members from marking the cue.

The cam 21 may be provided with suitable spring means or may be made in any suitable form, and after it is released in the operation which is described from the position as shown in Figure 3, it is swung around 110 to assume the position shown in Figure 1.

When it is desired to lock the cue in, the

member 21 is swung to a vertical position to engage through the ledge 22 therein, with the pin 20, preventing any downward movement of the holder to release the cue. When 5 so engaged, the cam in any well-known manner may be secured in this position by a suitable lock extending through an aperture therein registering with an aperture in the holder, thereby locking the cue in the holder 10 and preventing its removal.

In Figure 3, the cam member is extending downwardly and in engagement with the top of the supporting pin 20, the gripping members in this position and as shown being 15 open and ready to receive the top of a cue. On the cue top, as shown in dotted lines in Figure 3, being inserted between the gripping members, the cam member is swung to the right, releasing the pin and permitting 20 the device to assume the position shown in Figure 1 wherein the gripping members tightly hold the top of the cue.

To retain the gripping members in this position, the cam member is swung to the 25 left until it assumes a vertical position in which it is intended to engage with the underside of the pin 20, thereby preventing the device as a whole from being moved upwardly to any extent to release the cue. 30 In this position, the cam member can be readily locked by any suitable means in combination with the plate 10.

In other words, to grip the cue 23, the 35 cam member, assuming that it is in the position as shown in Figure 3, is first swung to the right, releasing its engagement with the pin 20. The device then slides on the pin until the pin reaches the top of the slide 19, which action causes the gripping members to close 40 around the top of the cue, as illustrated in Figure 1. To retain the holder in this position, the cam member is then swung to the left to engage with the underside of the pin 20 and then, even when the cue is pressed 45 upwardly, it will not be possible to release it or to open the gripping members 17, the upward movement of the holder being prevented by the engagement of the cam at the point 22 with the underside of the pin 20.

To release the cue, it is then necessary, as 50 above mentioned, to swing the cam member downwardly and to the right and then shove the cue upwardly, when the holder will slide upwardly until the pin reaches the bottom of the slide, thereby opening wide, as shown 55 in Figure 3, the gripping members.

It will be seen from the foregoing that this cam member practically controls the up-

ward and downward slideable movement of the holder and constitutes, therefore, a very 60 important feature in my invention.

As many changes could be made in the above construction and many apparently 65 widely different embodiment of our invention within the scope of the claims, constructed without departing from the spirit or scope thereof, it is intended that all matter contained in the accompanying specification and drawings shall be interpreted as 70 illustrative and not in a limiting sense.

What we claim as our invention is:

1. A cue holder comprising a metal strip slotted adjacent one end and having the other end doubled on itself to form an intermediate shelf or stop, a suitably bent rod 75 through the bottom of the folded end, a pair of S-shaped gripping members hingedly mounted on said rod, links pivotally connected to said gripping members and formed with looped ends designed to overlap to receive therethrough a supporting pin for the holder, said pin being also adapted to extend through said slotted end whereby the holder is slidably suspended in position, and cam means pivotally mounted adjacent said 80 slot and adapted to engage with the supporting pin to retain the holder in closed or open position.

2. A cue holder of the character described comprising, in combination, a supporting 90 pin, a slotted plate member adapted to be slidably suspended on said pin, a stop or cue-top rest formed intermediate of said plate, cue gripping members hingedly mounted on the plate, link members operatively connecting the gripping members with the supporting pin, and cam means 95 operatively mounted on said plate designed to control the upward and downward slideable movement of the holder.

3. A cue holder of the character described comprising, in combination, a slotted plate formed with a cue-top rest and provided with pivotally mounted gripping members link-connected to a pin member adapted to 100 slidably support the holder, and cam means on the holder designed to engage with said pin to securely retain the holder in an open or closed position.

In witness whereof we have hereunto set 110 our hands in the presence of two witnesses.

ADAM ANDRECK.
FRANK RUBCZYNSKI.
